(Cl. D58—6)

To all whom it may concern:

Be it known that I, Christy M. Del Mas, a citizen of the United States of America, residing at city, county, and State of New York, have invented a new, original, and ornamental Design for a Perfume Vial, of which the following is a specification, reference being had to the accompanying drawing, forming part thereof.

The rear view and side view not shown are the same as those shown.

I claim:

The ornamental design for a perfume vial, as shown and described.

CHRISTY M. DEL MAS.
